UNITED STATES PATENT OFFICE.

ROBERT G. LOWE, OF CLAWSON, MICHIGAN.

POWER-SIEVE.

1,357,292.

Specification of Letters Patent.

Patented Nov. 2, 1920.

Application filed April 12, 1920. Serial No. 373,243.

To all whom it may concern:

Be it known that I, ROBERT G. LOWE, a citizen of the United States, and residing at Clawson, in the county of Oakland and State 5 of Michigan, have invented a new and Improved Power-Sieve, of which the following is a specification.

This invention relates to means for shaking and agitating sieves and screens and 10 other containers, for foundry sand, builders' sand, other granular substances, and for liquids, and its object is to provide a device of this character which shall have maximum capacity, which shall be simple in construction and which shall not be liable to get out 15 of order.

This invention consists, in the combination of an electric motor comprising the usual armature and its shaft and a field 20 housing of any desired type, of a casing wherein the motor is mounted with its armature shaft upright, of an eccentric at one or both ends of the armature shaft journaled in said casing so that when the armature rotates, the upper part of the casing will be caused to move around in a circular path of small diameter, of means whereby this casing may be suspended, and a container, screen, sieve or riddle mounted above the 25 casing and connected thereto so that it will receive a rapid circular motion therefrom.

It also consists in the details of construction illustrated in the accompanying drawing and particularly pointed out in the 30 claims.

In the accompanying drawings, Figure 1 is an elevation of this improved sand sifting machine. Fig. 2 is a section on the line 2—2 of Fig. 1. Fig. 3 is a central vertical elevation of this improved machine. Fig. 4 is a section on the line 4—4 of Fig. 3. Fig. 5 is a vertical section of an improved type of eccentric for the upper end of the armature shaft on a larger scale. Fig. 6 is a central 40 vertical section of a modified form of this device. Fig. 7 is a section on the line 7—7 of Fig. 6.

Similar reference characters refer to like parts throughout the several views.

50 The screen, sieve or riddle 1 is held by the two segmental straps 2 which are mounted on posts 3 secured to the hollow cross bars 4 and 4^a which connect to the hollow frame bars 5 by means of T's 6. An eye 7 in the 55 connection 8 between the upper ends of the frame bars 5 furnishes a means of support

for the device and the wires 9 extend through these tubular bars 4 and 5 to the motor which actuates this device. Any other desired means may be used to support the mechanism hereinafter described. 60

A substantially cylindrical case 11 is formed with lugs 12 into which the tubes 4 and 4^a connect and this case has inwardly extending ears 13 at its upper end which are connected to the disk 14 by the screws 15. In this disk 14 is journaled an eccentric 16 which is secured to the upper end of the armature shaft 17. A U-shaped bracket 19 connects to this cylindrical casing 11 in any desired manner, the screws 20 being shown. This bracket has a hemispherical seat 22 for the ball 23 which supports the lower member 24 of the motor casing. The intermediate member 25 of the motor casing is provided with proper pole pieces 26 and the field coils 27. The lower portion 24 is provided with proper sockets 28 for the brushes 29 which engage the commutator 30 of the armature 31. The wires 9 extend from the tube 4 through a passage 33 in the casing 11 and connect to the brushes 29 and to the field coils 27, while a wire 34 connects the two field coils. Any other system of wiring and any desired type of motor may be employed. The motor casing is positioned by means of springs 35 mounted on pins 36 and 37 carried by the motor housing and by the disk 14 and bracket 19. The motor housing is permitted to oscillate freely by means of these springs but is prevented from turning 80 with the armature. 85

The lower end of the armature shaft 17 is mounted in a ball thrust bearing within the socket 39 formed at the middle of the lower portion 24 of the motor housing, which rests directly on the bearing ball 23. The upper end of the armature shaft is guided by the ball bearing 38 in the socket 40. 90 95

When the motor is energized and the 100 armature shaft 17 rotates, the eccentric 16 will cause the upper end of the motor housing to move in a circular path, the armature rotating within the housing in the usual manner. This movement of the armature and housing will cause the center of the riddle 1 to travel in a circular path and results in the contents of the riddle being sifted through at a very great speed. A cap 44 prevents sand getting to the eccentric 16. While the motor and its housing oscillate or gyrate in the casing, this action also 105 110

causes the casing, the frame and the screen or riddle to gyrate but in the opposite direction, which gyratory movement of the riddle so agitates the contents thereof that 5 they become sifted at maximum speed.

It will be understood that the eccentric 16 may be provided with any desired type 10 of friction reducing mechanism. In Fig. 5 I have shown this eccentric 16 provided with two grooves to receive the balls 41 which bear on the spherical surface 42 formed in the disk 14. The outer arms of the T's 6 are preferably open so as to admit air which may be agitated and circulated 15 by the fan 43 on the armature shaft. The usual air passages in the motor housing will permit this circulation.

In Figs. 6 and 7 a modified structure is shown. The same tubes 4 and 4^a are employed to support the motor and its housing. 20 The armature 46 is mounted on the shaft 47, whose upper end is connected to an eccentric 48 and whose lower end is connected to an eccentric 49. The eccentric 49 is journaled in a disk 50 by means of any desired 25 thrust bearing. The upper eccentric 48 is journaled in a disk 51 and any suitable ball bearing may be employed. The disks 50 and 51 fit within the cylindrical shell 55 which is provided with a door 56 of any 30 desired size to provide access to the motor. Connected to this shell 55 and to the disks 50 and 51 are two vertical bars 57 provided with the lugs 58 to receive the tubes 4 and 4^a and provided with ears 59 and 60 at 35 their ends which are secured to the disks 50 and 51 respectively by means of the screws 61.

The motor housing 62 has pole pieces 63 40 on which are the field coils 64 and mounted on this housing are two bars 65 which connect to the wires 66 and 67 leading to the brushes 68 and to the winding 64 respectively. A wire 69 connects the two field 45 windings 64 in the usual manner and pins 71 mounted in the disk 51 connect to the wires 9 leading in through the pipe 4. Ball bearings 75 and 76 provide for the support 50 of the motor housing 62 on the armature shaft. Caps 77 and 78 are employed to exclude dust and dirt from the eccentrics 48 and 49.

55 Springs 79 mounted on pins 80 and 81 permit the motor housing and the parts mounted therein and thereon to travel around in a circle when the armature ro-

tates, but they prevent the motor housing from turning on its own axis. Any other suitable type of electric motor may be employed. The action of this modified form 60 of sifter is even greater than that of the structure shown in Figs. 1 to 4. The fan 82 is repeated in this modification.

The sizes and proportions of the various parts and the details of the motor may all 65 be changed by those skilled in the art without departing from the spirit of my invention as set forth in the following claims.

I claim:—

1. The combination of an electric motor embodying a housing an armature and a vertical armature shaft journaled in the housing, a casing, an eccentric secured on one end of the armature shaft and journaled 75 in the casing, and means to suspend the casing.

2. A casing and a receptacle mounted thereon, an electric motor mounted within the casing having an armature shaft, and 80 means connecting the shaft and casing to cause one end of the shaft to travel in a circle relative to the casing and resilient connectors between the motor and casing.

3. A casing and an electric motor mounted 85 therein, said motor embodying a vertical armature shaft, an eccentric on each end of the armature shaft, a bearing for each eccentric in the casing, a frame to suspend the casing, and a receptacle mounted on the 90 frame.

4. A casing and an electric motor therein embodying a housing, an armature and a vertical armature shaft, an eccentric mounting for each end of the shaft, resilient 90 means to prevent the housing from turning in the casing, a frame and a receptacle mounted on the frame and means connecting the frame to the casing whereby gyratory movements may be communicated to 100 the receptacle from the casing.

5. A casing and an electric motor therein embodying a housing, an armature and an armature shaft journaled in the housing, resilient means permitting oscillatory movement but preventing rotary movement of the housing in the casing, and an eccentric on the armature shaft journaled in the casing to cause oscillation of the housing in the casing.

ROBERT G. LOWE.
